PREVENTION OF FOAMING IN STEAM
BOILERS

Paul G. Bird and Arthur L. Jacoby, Western
Springs, Ill., assignors to National Aluminate
Corporation, Chicago, Ill., a corporation of
Delaware

No Drawing. Application March 27, 1942,
Serial No. 436,491

6 Claims. (Cl. 252—321)

1

The present invention relates to antifoaming compositions which are used in steam boilers and similar steam generators, evaporators, etc., to overcome the tendency of the water therein to foam and hence to bring about the priming of the steam generator or the like.

One of the objects of the present invention relates to a liquid suitable for the generation of steam in steam generators and comprising water containing dissolved therein a very small quantity of an acyl derivative of an aromatic polyamine having a high molecular weight, whereby, when such water is heated to the boiling point in a steam boiler or other generator, being thereby evaporated, the concentration of solids therein will not bring about excessive foaming and the resulting priming, these compounds being substantially nonvolatile with the steam and stable, so that they will be retained by the water and neither they nor their decomposition products will appear in the steam and the resulting condensation thereof.

It is well known in the operation of steam boilers, such as in electric power plants, railroad locomotives and the like, or in evaporators, that the water therein, even though initially it shows very little tendency to foam, will, when the amount of total solids therein approaches a relatively high concentration, develop a very decided tendency to foam. When this occurs, considerable quantities of water are physically carried out of the boilers or evaporators with the steam, thus appearing in the steam lines and in the eventual condensate. Such priming has many disadvantages because it tends to contaminate the steam lines, to plug or corrode the valves, and under serious conditions may even impair the cylinders and piston rods of the steam engines, or the impeller blades of turbines in which the steam is used for the generation of power. Attempts have been made in the past to control this foaming, either by excessive blowdown of the boilers or by the injection thereto of such materials as castor oil, tallow, and the like. While these fatty materials have some small degree of efficiency, they are, on the other hand, quite deficient in that they introduce new difficulties which, in some instances, are worse than the conditions they are intended to cure. In the first place, these fatty acids or glycerides are unstable under the conditions existing in the boilers, particularly as the pressure and temperature increase, the high temperatures leading to rapid decomposition of the glycerides, which, if anything, will tend to increase the foaming and priming difficulties.

2

Furthermore, in many instances certain of the decomposition products thus produced, or sometimes even the materials themselves, have a definite volatility with steam and will, therefore, steam-distil out of the boilers, thus appearing in the steam and in the condensate. This, of course, is also very undesirable. Furthermore, such types of antifoaming agents usually have to be employed in relatively large quantities, adding not only to the expense but also to the inconvenience of operating the steam generators; and those which have a tendency to decompose do so quite rapidly, and hence their effectiveness is of short duration, which therefore necessitates the continual charging into the boilers or other steam generators of relatively large amounts of these older antifoaming agents. Moreover, such antifoaming agents are difficult to use because the amounts in which they are efficacious are very critical, and any overdosage usually aggravates the difficulty instead of curing it.

Applicants have now discovered, however, that there is a series of compounds which may broadly be designated as acyl derivatives of aromatic polyamines, wherein the acyl groups are derived from high molecular weight aliphatic acids, and which are of a high order of efficiency when used as an antifoaming and antiprimer agent in steam generators. These acyl derivatives must, however, meet certain requirements as to molecular weight and configuration, as will be fully discussed below.

The materials of the invention may be represented by the probable general formula:

wherein Y and Z represent aliphatic hydrocarbon radicals which may contain one or more double bonds and may be substituted by hydroxyl groups; that is, the groupings $Y-CO-$ and $-OC-Z$ stand for acyl radicals of saturated or unsaturated fatty acids or hydroxy fatty acids; and X represents the residue from an aromatic polyamine which may be varied considerably and which is a member of the group including the phenylenediamines, diaminodiphenylamines, diaminobenzophenones, naphthalenediamines, benzidine, diaminodiphenyl ethers, N-alkylated phenylenediamines, and diaminodiphenyls where the primary amino groups are on the same or different rings.

It is to be understood that the formulas recited in the claims are "probable" in that the formulas given are believed to be possessed by the compounds disclosed, or whose method of preparation is disclosed in this specification.

In further regard to the radicals $Y-CO-$ and $-OC-Z$, it is not necessary that they both be derived from the same fatty acid, and in fact one may be relatively small, as for example, acetyl, when the other contains at least about 16 carbon atoms, but in the case where they are substantially equal in number of carbon atoms, each must contain at least about 14.

Specific compounds which have been shown to be efficient as antifoaming and antipriming agents include the products from the condensation of oleic acid with m-phenylenediamine, stearic acid with m-phenylenediamine, palmityl chloride with 4,4'-diaminobenzophenone, palmityl chloride with 4,4'-diaminodiphenyl ether, 15 stearic acid with N-methylphenylenediamine, stearic acid with p-phenylenediamine, and palmityl chloride with benzidine.

Many of the products useful in connection with the present invention may be obtained in more than one way. The examples given below are merely illustrative of methods of preparing a few representative members of the group.

Example 1.—A mixture of 19.8 grams of oleic acid and 3.2 grams of m-phenylenediamine was heated with stirring at 150°–160° C. for 3.5 hours. When cool, the product was a dark brown, viscous oil.

Example 2.—A mixture of 24.2 grams of commercial stearic acid and 4.3 grams of m-phenylenediamine was heated with stirring at 150°–160° C. for 3 hours. When cool, the product was a hard, black wax.

Example 3.—To a stirred and heated portion of palmityl chloride weighing 22 grams was added slowly, with stirring, 8.5 grams of 4,4'-diaminobenzophenone. During the addition, the temperature of the mixture was gradually increased from about 100° C. at the beginning to a maximum of 190° C. at the end. Much hydrogen chloride was evolved during the addition. When cool, the product was a very high melting wax.

Example 4.—To 22 grams of palmityl chloride was added slowly, and with stirring, 8 grams of 4,4'-diaminodiphenyl ether. The temperature of the mixture was gradually increased during the addition from about 100° C. at the start to about 190° C. at the end. Hydrogen chloride was freely evolved during the addition; and the product, when cool, was a hard, crumbly, dark wax.

Example 5.—A mixture of 11.8 grams of commercial stearic acid and 2.5 grams of methyl p-phenylenediamine was heated with stirring at 150°–160° C. for 3 hours. When cool, the product was a brown wax.

Example 6.—A mixture of 16.9 grams of commercial stearic acid and 5.4 grams of p-phenylenediamine was heated with stirring at 150°–160° C. for 3 hours. When cool, the product was a brown wax.

Example 7.—To 22 grams of palmityl chloride, 7.4 grams of benzidine was added slowly with stirring and heating. During the addition, the temperature was increased from about 100° C. at the start to about 250° C. at the end. Hydrogen chloride was freely evolved during the addition; and when the product was cool, it was an extremely hard wax.

Example 8.—To 16.5 grams of palmityl chloride at 150°–160° C. was added, with stirring, 6 grams of 2,4-diaminodiphenylamine, over a 10-minute period. After addition was complete, the stirring and heating were continued an hour. When cool, the product was a brown, sticky wax.

Example 9.—5.4 grams of o-phenylenediamine

and 30 grams of stearyl chloride were mixed at room temperature and heated with stirring at 150°–160° C. for an hour. When cool, the product was a brown wax.

The compounds mentioned herein, while not ordinarily considered as soluble in water to any great extent, may be suitably dispersed in water or emulsified therewith, so that effective amounts thereof may be introduced and be present in the water within the steam generator under operating conditions. The emulsifying or dispersing agent used must, however, be of a kind that does not cause foaming, either by itself or by its decomposition products. The compounds may be used conjointly with each other as well as with other known antifoaming agents, such as, for example, castor oil.

The amounts of these acyl derivatives of aromatic polyamines, of high molecular weight, which are required are extremely small, and in general one grain per gallon is ample. For many purposes, however, amounts of as little as $\frac{1}{100}$ grain per gallon in the feed water will still give valuable results, and the amounts may be even further reduced. Depending of course upon the degree of concentration of solids, the dosage may be varied, but one grain per gallon is about as much as would ever have to be used even under serious conditions, and for many purposes $\frac{1}{100}$ grain per gallon and even less can be used. The process is particularly effective at pressures of about 250 pounds per square inch.

The introduction of the antifoaming compounds of the present invention into the boiler may be accomplished in a number of ways. Thus, the antifoaming compositions may be dispersed or physically mixed with, say, sodium carbonate or some other material used for treating the boiler water and pumped with the feed water into the boiler by means of either an injector or a feed water pump. The compounds may also be dissolved in suitable organic water-miscible solvents such as alcohols, ethers, ketones, etc. and introduced in small measured amounts into the feed water entering the boiler. Suitable mechanical measuring devices which will periodically or continuously inject the required dosage of the antifoaming compounds into the feed water may be used, so that the introduction will be more or less in proportion to the steam consumption to which the steam generator is subjected. Another manner of introducing the antifoaming compounds is to form an emulsion thereof in water and then feed said emulsion either directly into the boiler or the feed water lines leading to it. The invention therefore is not to be limited by the manner of introduction of the antifoaming composition but rather is to be construed in the terms of the hereunto appended claims.

We claim:

1. Process of minimizing the production of foam in and the priming of steam generators operating at superatmospheric pressures which comprises incorporating with a water therein containing an amount of total solids tending to produce foaming and priming a quantity of a diacyl derivative of an aromatic polyamine sufficient to substantially inhibit priming and foaming, said acyl group containing at least about 16 carbon atoms.

2. Process of minimizing the production of foam in and the priming of steam generators operating at superatmospheric pressures which comprises incorporating with a water therein a quantity of a diacyl derivative of a phenylenediamine in which each of the acyl groups contains at least

14 carbon atoms, said quantity being sufficient to substantially inhibit priming and foaming.

3. Process of minimizing the production of foam in and the priming of steam generators operating at superatmospheric pressures which comprises incorporating with a water therein a quantity of a condensation product of metaphenylenediamine and stearic acid, sufficient to substantially inhibit priming and foaming.

4. Process of minimizing the production of foam in and the priming of steam generators operating at superatmospheric pressures which comprises incorporating with a water therein a very small amount of a condensation product of palmityl chloride and 4,4'-diaminobenzophenone, sufficient to substantially inhibit priming and foaming.

5. Process of minimizing the production of foam in and the priming of steam generators operating at superatmospheric pressures which comprises incorporating with a water therein a very small amount of a condensation product of palmityl chloride and benzidine, sufficient to substantially inhibit priming and foaming.

6. The process of conditioning water for the generation of steam under superatmospheric pres-

sures so as to impart to said water improved non-foaming boiling characteristics which comprises incorporating with said water, containing an amount of total solids tending to produce foaming and priming, not substantially more than about 1 grain per gallon of a diacyl derivative of an aromatic polyamine in which one of the acyl residues contains at least about 16 carbon atoms, said quantity of diacyl derivative of an aromatic polyamine being sufficient to substantially inhibit priming and foaming.
